Primary Examiner — Kevin K Rudzinski*Assistant Examiner* — Paul D Bohannon(74) *Attorney, Agent, or Firm* — Lewis Roca Rothgerber Christie LLP(57) **CLAIM**

The ornamental design for a chaise, as shown and described.

DESCRIPTION

FIG. 1 is a front and right side perspective view of an exemplary chaise showing my new design in a first configuration, where the seat back is inclined;

FIG. 2 is a front elevation view thereof;

FIG. 3 is a right side elevation view thereof, the left side being a mirror image;

FIG. 4 is a rear elevation view thereof;

FIG. 5 is a top plan view thereof; and,

FIG. 6 is a front and right side perspective view of an exemplary chaise showing my new design in a second configuration, where the seat back is reclined.

The broken lines show environmental subject matter and form no part of the claimed design. The fragmentary showing of a weave pattern in the drawing figures is understood to be repeated throughout the surfaces shown.
